UNITED STATES PATENT OFFICE

2,407,797

BOOKRACK OR CASING

Willis L. Ramsey, Parma, Mo.

Application October 27, 1944, Serial No. 560,635

3 Claims. (Cl. 211—42)

1

This invention relates to cabinets for holding books, such as catalogs or the like, provided with means for suspending the books in compartments in a desk or cabinet-like structure, in which book holders are provided that are movable from a closed position where the books are suspended in the cabinet to an open position where the book holders are caused to assume an approximately horizontal position at the top of the cabinet, where the books can be opened for consultation and reading.

It is an object of the invention to provide a cabinet with one or more book holders or carriers, swingingly or pivotally mounted with relation to the casing and comprising a block or base having an aperture to receive a pivot, and provided with means by which the book may be detachably held in place thereon; means being also provided for permitting a book backing or cover to be hinged to the book holder.

It is a further object of the invention to provide a cabinet of the character indicated whereby the book holder may be moved from within the cabinet to the top thereof, in which latter position it is held by the opened book resting on the top of the cabinet or the tops of the other units of the cabinet, and the relation of parts is such that when the book is closed, the holder assumes its position within the cabinet by gravity after it has been tilted off center by lifting the end of the holder at the front of the cabinet.

It is a still further object of the invention to produce a cabinet or rack in which the books may be installed or removed expeditiously, and in which the holding means operate in conjunction with relatively thin or thick books, within predetermined bounds.

With the foregoing and other objects in view, the invention consists in the details of construction, and in the arrangement and combination of parts to be hereinafter more fully set forth and claimed.

In describing the invention in detail, reference will be had to the accompanying drawings forming part of this application, wherein like characters denote corresponding parts in the several views, and in which:

Figure 1 illustrates a top plan view of a cabinet or rack showing the book holders in plan;

Figure 2 illustrates a view in elevation of the rear side of the cabinet;

Figure 3 illustrates a plan view showing the details of the book holder;

Figure 4 illustrates a vertical sectional view longitudinally of the cabinet;

2

Figure 5 illustrates a sectional view on the line 5—5 of Fig. 2;

Figure 6 illustrates a sectional view similar to Fig. 5 with the carrier in open position;

Figure 7 illustrates a sectional view on the line 7—7 of Fig. 3; and

Figure 8 illustrates a sectional view of a book having an aperture for the reception of the means for holding it on the carrier.

In these drawings a substantially rectangular frame having parts generally identified by the numeral 10 is provided with a front panel 11 and end panels 12 and a plurality of partitions 13 spaced from one another to form compartments, in which the book holders operate and in which the books are suspended. The book carriers each comprises a rectangular head 14 having a width approximating that of a compartment in which it operates between the partitions. A pivot pin 15 has its ends lodged in the ends of the cabinet and it extends through apertures of the partitions and through apertures of the book carrier so that the book carrier may swing or oscillate on the pivot. The upper side edges of the book carrier are beveled as at 16, to provide a clearance for the book backings 17 which are attached to the carriers by hinges 18, as fully shown in Fig. 7, the hinges being secured to the carriers by fastenings 19, such as screws or the like. The book carriers are provided with shoulders on which the inner butts 21 of the hinges are seated, so that the upper surface of each butt of the hinge is in line with the upper surface of the carrier; furthermore, the said shoulders are provided with screw eyes 22 at each side of the carrier between which the back of the book 23 is stationed, the said book having a transverse aperture, such as 24, shown in Fig. 8, through which is laced the book retaining device, such as a thong 25 or flexible member 25, which passes through the apertures of the book and through the eyes of the screws, substantially as shown in plan, Fig. 3, the ends of the flexible member or thong being secured to the carrier in appropriate manner, as by staples or tacks 26, conventionally shown in Fig. 3.

After the books have been installed on the book carriers, each of said book carriers may be swung to the position in which it is shown in Fig. 5 which may be regarded as the normal position of the book carrier, when the books are within the cabinet, or the book carrier may be turned to the position in which it is shown in Fig. 6 when the book is exposable on the top of the cabinet. The book carrier has two shoulders or flanges 27 and

28, the former of which engages the upper surface of the top of the cabinet to limit the movement of the book carrier and retain it in open position when the book is open, whereas the shoulder 28 engages the under surface of the rail or strip of material 10' connected to the partitions 13 and front panel 11, which the shoulder 28 abuts when the carrier is swung to a closed position, as shown in Fig. 5 and, in operation, when the book carrier is lifted from its position as shown in Fig. 6 to disengage the shoulder 27 from the top of the cabinet, the carrier by gravity assumes the position in which it is shown in Fig. 5 and the weight of the book serves to retain the parts in the closed position.

While the drawings show the book carrier as having a single book installed in each compartment, it is obvious that a plurality of thin books, price-lists, catalogs or other informative publications may be nested or assembled on the book carrier and provided with apertures for the lacing, so that other than a single book may be stored in each compartment.

I claim:

1. In a device of the character described, a frame having upright partitions mounted thereon, a member connected to the top at an outer edge of each partition, a pivot supported by the partitions near their upper edges, book carriers in the spaces between the partitions oscillatably mounted on the pivot, shoulders on the ends of each book carrier for alternately engaging the upper and lower surfaces of said member of the frame whereby the book carrier is arrested in its movement when oscillated, book backings associated with each of the book carriers, a hinge by which each book backing is mounted on the book carrier, said book carrier having recesses in its side edges forming clearances for the butts of the hinges, means for securing the hinges to the book carrier and book backing, respectively, and means on the book carrier for holding a book thereon.

2. In a device of the character described, a frame having upright partitions mounted thereon, a member connected to the top at an outer edge of each partition, a pivot supported by the partitions near their upper edges, book carriers in the spaces between the partitions oscillatably

mounted on the pivot, shoulders on the ends of each book carrier for alternately engaging the upper and lower surfaces of said member of the frame whereby the book carrier is arrested in its movement when oscillated, book backings associated with each of the book carriers, a hinge by which each book backing is mounted on the book carrier, said book carrier having recesses in its side edges forming clearances for the butts of the hinges, means for securing the hinges to the book carrier and book backing, respectively, means on the book carrier for holding a book thereon, said means comprising stationary elements on the book carrier in spaced relation to each other transversely of the book carrier, the space between the stationary elements being adapted to receive the back of the book, a flexible member threaded through apertures of the book and attached to the stationary elements, and means for securing the flexible member to the carrier.

3. In a device of the character described, a frame having upright partitions mounted thereon, a member connected to the top at an outer edge of each partition, a pivot supported by the partitions near their upper edges, book carriers in the spaces between the partitions oscillatably mounted on the pivot, shoulders on the ends of each book carrier for alternately engaging the upper and lower surfaces of said member of the frame whereby the book carrier is arrested in its movement when oscillated, book backings associated with each of the book carriers, a hinge by which each book backing is mounted on the book carrier, said book carrier having recesses in its side edges forming clearances for the butts of the hinges, means for securing the hinges to the book carrier and book backing, respectively, means on the book carrier for holding a book thereon, said means comprising screw eyes anchored in the carrier and spaced apart transversely of the carrier a distance to form a clearance for the reception of a book back, a flexible element threaded through the transversely disposed apertures of the book and through the openings of the screw eyes for retaining the book in position, and means for anchoring the ends of the flexible member to the said carrier.

WILLIS L. RAMSEY.
